(57) **CLAIM**

I claim the ornamental design for a sheet material dispenser, as shown and described.

DESCRIPTION

FIG. 1 is a perspective view of a sheet material dispenser showing my new design;

FIG. 2 is a right side view thereof;

FIG. 3 is a left side view thereof;

FIG. 4 is a rear view thereof;

FIG. 5 is a front view thereof;

FIG. 6 is a top plan view thereof;

FIG. 7 is a bottom plan view thereof; and,

FIG. 8 is a bottom perspective view thereof.

The shade lines in the Figures show contour and not surface ornamentation.

The unshaded area between the solid and broken lines form no part of the claimed design.

The broken lines in the drawings depict portions of the sheet material dispenser that form no part of the claimed design.
